UNITED STATES PATENT OFFICE.

JOHN BROUH, OF PHILADELPHIA, PENNSYLVANIA.

DOUBLE-HUNG WINDOW SASH.

Application filed February 7, 1927. Serial No. 166,562.

This invention relates to window constructions.

The object of the invention is to provide double hung window sashes with pivoted glass sashes constructed and arranged to be swung upon the pivots to permit cleaning the outside of a window from the inside of a dwelling.

Another object of the invention resides in the provision of a window glass sash swingingly mounted in a sliding window sash, the sashes having grooves adapted to register, into and out of which may slidably move a combined locking and sealing plate whereby to fasten the swinging sash against swinging movement and to exclude air from the room, and whereby the combined fastening and air sealing device may be moved to permit swinging movement of the swinging sash.

With the above and other objects in view, the invention consists in the construction and novel combination and arrangement of parts hereinafter fully described, illustrated in the accompanying drawings and pointed out in the claims hereto appended, it being understood that various changes in the form, proportion and minor details of construction, within the scope of the claim, may be resorted to without departing from the spirit or sacrificing any of the advantages of the invention.

In the drawings:

Figure 1 is a front elevation of a window construction embodying a window frame and upper and lower sliding sashes, in each of which is pivoted a glass sash.

Fig. 2 is an enlarged detailed longitudinal sectional view.

Fig. 3 is an enlarged detailed cross sectional view.

Fig. 4 is a detail view of the combined locking and air excluding means for the swinging sashes.

Referring now more particularly to the accompanying drawings, the reference character 5 indicates a window frame in which the upper and lower sashes 6 and 7 are slidably mounted in the usual manner and provided with the usual sash balances (not shown). Each sliding sash has a groove 8-9 in the inner faces of its opposite sides for a purpose presently understood.

A glass swinging sash 10 is swingingly mounted in each sliding sash, and at each side each glass sash 10 is provided in its outer face with a longitudinal groove 11

adapted to normally register with the respective grooves 8-9 of the respective sliding sashes 6 and 7. The swinging or pivotal mounting of the glass sashes 10 may be effected in any suitable manner. One way of accomplishing this is to provide each glass sash 10 with suitable pivots on opposite sides thereof for engagement in the channel bearing sockets 13 of the upper and lower sashes 6 and 7.

A suitable device for locking the swinging glass sashes against swinging movement and to exclude air, is provided, there being a pair of devices for this purpose associated with each of the upper and lower window sashes. In the drawings there is a locking plate 14 adapted normally to cover the joint at each side of each of the upper and lower windows, the plate 14 lying in the respective grooves of the sliding and swinging sashes and being disposed over the joint to lock the swinging sashes against movement and exclude air at the sides of the sashes. Each plate 14 has a lateral projection 15 which extends into a recess 16 in the side of the respective sliding sash, and along its lower edge each projection 15 is provided with gear teeth 16a. A pinion 17 is mounted in each side of each sliding sash on a shaft 18 which has its outer end journalled in a bracket 19 on the respective sliding sash and projecting through the bracket sufficiently to permit the application of a suitable tool (not shown) for rotating the pinion 17.

By rotating the respective pinions 17 in one direction it will be understood that the plates 14 will be withdrawn from the respective grooves in the sides of the swinging glass sashes beyond the side joints between the latter and the sliding sashes, so as to permit swinging movement of the sashes on their pivots 12. Upon bringing the swinging sashes into closed relation with the sliding sashes, the rotating of the pinions in the opposite directions effects locking of the swinging sashes against swinging movement and also prevents air passing between the sides of the swinging and sliding sashes. The plates 14 are of a length substantially the length of the swinging sashes.

From the foregoing it will be seen that I provide a window construction wherein the usual sliding sashes carry swinging glass sashes so as to permit the cleaning of the outside of the glass from the inside of the dwelling, and that the swinging glass sashes

may be held in locked position by a device which effects not only the locking but serves as an air sealing device at the sides of the cooperating sashes.

5 What is claimed is:

In a window construction, a window frame, upper and lower sashes slidable in the frame and each having a recess and also a longitudinal groove in the inner face of each side, a glass sash pivoted in each sliding sash and each provided with a longitudinal groove in the outer face of each side to align with the respective grooves of the respective sliding sashes, a plate mounted in the aligning grooves of the sliding and swinging sashes at each side of the latter

and each plate having an integral, flat lateral projection intermediate its ends extending into the respective recesses of the sliding sashes, one edge of each projection having 20 teeth, a pinion journalled in each recess of each sliding sash at each side thereof and meshing with the teeth of the respective projection whereby to shift the respective plates out of the respective grooves of the 25 swinging glass sashes to permit swinging movement of the latter, the pivots of the glass sashes being spaced from the plates and their projections.

In testimony whereof I have hereunto set 30 my hand.

JOHN BROUH.
